TOY GLIDE PLANE

Aristidis G. Tombros, Los Angeles, Calif., assignor to
E&A Manufacturing Co., Beverly Hills, Calif., a partnership

Filed June 1, 1962, Ser. No. 70,382

Term of patent 7 years

(Cl. D34—15)

Fig. 1

Fig. 2

Fig. 3

Fig. 4

FIGURE 1 is a perspective view of the novel design
of my toy glide plane;

FIGURE 2 is a top plan view thereof;

FIGURE 3 is a front elevational view thereof; and

FIGURE 4 is a side elevational view.

I claim:

The ornamental design for a toy glide plane, sub-
stantially as shown.
